(57) **CLAIM**

The ornamental design for a batting tee attachment, as shown and described.

DESCRIPTION

FIG. 1 is a top-front-left perspective view of a batting tee attachment showing my new design;

FIG. 2 is a bottom-rear-right perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof;

FIG. 8 is a bottom plan view thereof; and,

FIG. 9 is a cross sectional view thereof, taken along line 9-9 in FIG. 6.
The broken lines depicting the cavity on FIGS. 1, 7 and 9 forms no part of the claimed design.
